(57) **CLAIM**

I claim the ornamental design for armrests for seat, as shown and described.

DESCRIPTION

FIG. 1 is a top perspective view of the first of a pair of armrests for seat;

FIG. 2 is a rear elevation view thereof;

FIG. 3 is a front elevation view thereof;

FIG. 4 is a right side elevation view thereof;

FIG. 5 is a top plan view thereof;

FIG. 6 is a left side elevation view thereof;

FIG. 7 is a bottom plan view thereof;

FIG. 8 is a top perspective view of the second of a pair of ARMRESTS FOR SEAT;

FIG. 9 is a rear elevation view thereof;

FIG. 10 is a front elevation view thereof;

FIG. 11 is a right side elevation view thereof;

FIG. 12 is a top plan view thereof;

FIG. 13 is a left side elevation view thereof; and,

FIG. 14 is a bottom plan view thereof.

The broken lines of FIGS. 1-14 depict boundaries that are not part of the claimed design.
